UNITED STATES PATENT OFFICE.

JOSEPH REGENSTEIN, OF CHICAGO, ILLINOIS.

DOOR-PANEL AND THE LIKE.

1,259,287.

Specification of Letters Patent. Patented Mar. 12, 1918.

Application filed July 23, 1917. Serial No. 182,299.

To all whom it may concern:

Be it known that I, JOSEPH REGENSTEIN, a citizen of the United States, residing at Chicago, in the county of Cook and State 5 of Illinois, have invented certain new and useful Improvements in Door-Panels and the like, of which the following is a specification.

The present invention has to do with certain improvements in the construction of door panels and the like, and has particular reference to the construction of door panels for use in automobile construction. It will 10 presently appear that the features of the invention are not by any means limited to this particular class of service.

In the construction of doors for automobile bodies, it is very customary to provide a finishing panel for the interior face of 15 the door, which panel is secured to the body portion of the door in any suitable manner, as, for example, by the use of brads or nails. The appearance and finish of the door panels should harmonize with the interior finish 20 of the car. The use of leather finishings has come into very extensive favor, and has found very wide application. Nevertheless the use of real leather for this purpose is in 25 most cases out of the question on account 30 of its prohibitive cost. Other expedients have, therefore, been adopted for constructing the panels from some material other than leather, and providing them with the necessary finish to give the appearance of 35 being made of genuine leather. For this purpose, the use of cloth has found considerable favor, and the cloth or canvas is generally mounted on a suitable backing to 40 which it is attached, and by which it is supported and given additional strength and firmness. In the ordinary operation of the 45 car, the rain and elements naturally reach the door panels to a greater or less extent. Furthermore, during the washing or cleaning 50 of the interiors of the car bodies, the water, of necessity, strikes the panels and flushes them. For these and other reasons it is quite necessary to so construct the door panels that the water will be prevented from 55 entering their edge portions, because such water will soak into the edge portions of the panels and loosen up the cloth surfacing from its backing. In order to provide against this possibility, it has been a common expedient in the past to fold the edge portion of the cloth surfacing over the edge

of the pasteboard or other backing, so that the edge of the panel is protected by the cloth itself. This, however, is a tedious and expensive process and it involves the waste 60 of a considerable percentage of the cloth or canvas material. One of the objects of the present invention is to provide a door panel of such construction as to overcome the foregoing objection to these imitation 65 panels.

In order to give the panels a more finished and natural appearance, it has been quite customary in the past to emboss the cloth or canvas finishing before the same is 70 applied to the paste-board or card-board backing. As a result of this fact, it has been found that the moisture of the paste or glue has, to a large extent, destroyed the embossed finish, or at any rate has so softened the cloth or canvas that upon the application of the roller or other tool for 75 pressing the cloth or canvas against the paste-board backing, the embossed finish has been destroyed along definite lines or 80 strips. Furthermore, the connection between the cloth or canvas and the paste-board backing has been necessarily more or less imperfect, because of the rough nature of 85 the cloth surface as compared to the smooth nature of the card-board or paste-board backing.

Another object of the invention is to overcome the foregoing objections by so constructing the door panel that the embossing will extend clear through the card-board or paste-board backing, as well as the cloth or canvas finishing. This is done by 90 performing the embossing operation after the canvas or cloth covering has been applied. 95

In the manufacture of the door panels, material and labor can be saved by applying the cloth finish to a comparatively large surface of backing material, and thereafter 100 cutting this large surface or body into a number of blanks of the exact size and shape of the door panels. This procedure, however, necessarily results in the production of door panels having raw or exposed 105 edges, so that if they were to be left in this condition the water and elements would readily find and work their way in between the cloth and the backing.

Another object of this invention is to provide a panel of such construction that the edge thereof shall be amply and adequately 110

protected against the possible entrance of water between the cloth and the backing. This protection is, in most cases, secured by a system of sewing or stitching around the edges of the panels, and in other cases by the application of a strip or binder of cloth or the like folded around the entire edge of the panel.

Other objects and uses of the invention 10 will appear from a detailed description of the same which consists in the features of construction and combinations of parts hereinafter described and claimed.

Referring to the drawing: 15 Figure 1 shows a face view of a door having applied thereto a panel embodying the features of the present invention, the wall surrounding the door being broken away in fragmentary manner.

20 Fig. 2 shows on greatly enlarged scale, in fragmentary form, an edge portion of a door having applied thereto a panel embodying the features of the present invention.

Fig. 3 shows a fragmentary edge view of 25 the panel embodying the features of the present invention, the same being an edge view of a panel in which the edge protection is afforded by a system of sewing or stitching.

30 Fig. 4 is a front face view corresponding to Fig. 3.

Fig. 5 is a back face view corresponding to Figs. 3 and 4.

Fig. 6 is a front face view of a fragment 35 of a door panel embodying the features of the present invention, and in which the protection to the edge of the panel is afforded by way of a strip of binder or the like surrounding the same; and

40 Fig. 7 is a section through the construction shown in Fig. 6.

As previously mentioned, the door panel to which the present invention relates is conveniently built or made up by the application of a strip or sheet of canvas or the like to one face of a card-board or paste-board backing. This is ordinarily done while both the canvas or cloth and backing material are in their raw condition. The large sheet is then embossed so that the roughening or corrugating extends clear through both the cloth and the paste board backing. Thereafter, the cloth or canvas is coated with a water-proof and coloring material to render the same water-proof, and at the same time give it the blackened or brownish finish desired. This large sheet is then cut up into blanks of the size and shape of the door panels, thereby exposing the raw edge previously mentioned. The blanks thus formed then have their edge portions protected by a line of sewing or stitching, or in some cases by the application of the strip of binder.

45 Referring now to the several figures, the

door body is represented by the dish-shaped panel 8 which may be of metal or other suitable material. A wooden spacing block 9 is generally provided within the frame panel 8, said block serving to space the door panel 70 from the case 8, and serving also as a base or foundation upon which to apply the door panel.

The door panel 10 comprises the sheet of backing material 11 and the cloth or canvas 75 covering 12. The general shape of the panel is revealed in Fig. 1, although, of course, the particular shape in each case may be dictated by the job in hand.

The cloth or canvas covering 12 is pasted 80 or glued to the backing 11. The material is then embossed or corrugated, so that the embossing or roughening extends clear through both thicknesses of material. This fact is well illustrated and revealed in Figs. 2 and 85 7. It is also apparent from examination of Figs. 4 and 5, because these figures illustrate the reverse faces of the panel.

After the cloth or canvas facing 12 has been applied and the embossing performed, 90 the cloth or canvas is protected by coating the same with water-proofing and coloring material. The panel is then cut up into the desired shape, and thereafter a line of stitching or the like 13 is applied to the entire 95 periphery of the panel. This stitching may be of any suitable form and may be performed on any desired machine. There are in the market at the present time various forms of machine, whereby stitching may be applied 100 to the edge of a cloth or similar sheet, so as to protect the same, and any suitable machine may be used for applying this stitching 13. Or for that matter the stitching may be applied by hand. The desirable 105 thing is that the edge portion of the panel shall be bound or stitched together so as to effectively prevent the entrance of water or moisture between the cloth and the backing. In the stitching shown, the edge portion of 110 the panel is fully protected as shown by Fig. 3, from which it appears that the stitching 13 tends across the edge of the panel and just outside of the edge. Other portions of the stitching extend through the material of 115 the panel, as shown in Figs. 4 and 5.

After the stitching has been completed, the panel is attached to the backing 9 by the use of brads or tacks 14, as shown in Fig. 2. In order to give the door a more finished and 120 completed appearance, a finishing strip 15 is applied at the same time to the edge of the panel. This strip is conveniently made up from a strip of leather or the like folded over a cord 16, the completed strip being 125 of sufficient width to hide and protect the stitching around the edge of the door panel.

In the modified arrangement shown in Figs. 6 and 7, a binding strip 17 is substituted for the stitching illustrated in the pre- 130

ceding figures. The edge portion of this binding strip may be held in place by a line of stitching 18 extending clear through the panel and through the binding strip.

5 While I have herein shown and described only certain embodiments of the features of my invention, still it will be understood that I do not limit myself to the said embodiments, except as I may do so in the claims.

10 I claim:

1. As a new article of manufacture, a door panel or the like comprising a backing of paste-board or the like having pasted or glued to its exposed surface a facing of textile fabric of desired weave, the entire panel being embossed by corrugations or roughening extending through the backing and facing, and a line of stitching extending around the periphery of the panel and through both the backing and the facing thereof, and serving to firmly secure the facing to the backing and prevent the entrance of water into the edge of the panel, substantially as described.

25 2. As a new article of manufacture, a door panel or the like comprising a backing of paste-board or card-board having glued to one of its surfaces a facing of textile fab-

ric, there being corrugations or roughening extending entirely through both the backing and facing, and means for protecting the edge of the panel against the entrance of water into said edge, substantially as described.

3. As a new article of manufacture, a door panel or the like comprising a backing of suitable fibrous material having applied to its exposed surface a facing of textile fabric, there being corrugations or roughening extending through both the backing and the facing of the panel, and means for protecting the edge of the panel against the entrance of water between the backing and facing thereof, substantially as described.

4. As a new article of manufacture, a door panel or the like comprising a backing of fibrous material having pasted or glued to one of its faces a facing of textile fabric, and having applied to said textile fabric a suitable water-proofing material, there being corrugations or roughening extending through both the backing and the facing of the panel, and means for protecting the edge of the panel against the entrance of water thereto, substantially as described.

JOSEPH REGENSTEIN.
